UNITED STATES PATENT OFFICE

2,636,323

ELECTRIC GRINDER

Hans Skreberg, Big Bend Township,
Chippewa County, Minn.

Application February 7, 1952, Serial No. 270,405

1 Claim. (Cl. 51—166)

1

The object of my present invention is to provide an electric grinder having advantages over conventional grinders, one being a horizontally rotatable grinder spindle assembly that can be rotated the full 360° of a circle. Another advantage is a vertically arranged motor that has its case connected to the said grinder head assembly by means of a tube, hence the motor's case can be rotated in unison with the grinder head assembly, eliminating all reactive force between the motor's armature shaft and the upwardly extending extension shaft having a bevel or mitre gear that engage a mitre gear or pinion on the horizontally arranged grinder wheel shaft.

By providing a means for locking the grinder spindle at any point of its horizontal travel from zero to quarter, half, or other fractional movement that it may be desirable to position the grinder spindle, grinding of long bars, sickles, etc., is possible without moving the machine, or that might otherwise require placing the grinder at a distance from a wall or other obstruction that would interfere with working space in the shop where other machines are installed and used by the workman.

Other advantages, such as quick removal of grinder spindle by removing the four bolts that secure the grinder spindle's four journals to the tubular extensions of a T-member that forms the attaching medium of said tubular extension members to the vertical tube's upper end, for the purpose of substituting saws or other tools for the grinder head, attaching a table to the tubular extensions, etc., converts the grinder to a wood-working or other purpose machine.

In Fig. 1 in the drawing 1 represents frame members secured to a top member 2 and a platform member 3, forming a square stand with outwardly sloping legs extending below the platform member 3. An electric motor having on its bottom end of the case a centrally located pivot 21 engaging a circular hole 22 in the central part of the platform member 3, the top end of the motor case 4 is connected by studs 5 and plate 6 with a tube 7, the said tube 7 extending upwards and beyond top face of the frame member 2 through a central hole in said frame member or cap 2, and the extreme upper end of tube 7 has a T-member 8 and tubular extensions 9.

Journals 10 are secured to tubular extensions 9 by means of bolts 11, and journals 10 carry the horizontal shaft 12 to which gear 13 is secured.

The shaft 14 connected to motor's armature shaft end by flexible coupling 17 extends upwards inside the tube 7 and has the gear 15 that forms the drive for gear 13 of shaft 12 which has the grinding wheels 16. A clamp 17 in connection with the member 18 forms a locking device for the tube 7 and the T-member 8.

2

The electric power circuit (preferably the positive side) is connected to insulated collar 19 which is mounted on tube 7 by means of brush 20. Collar 19 is in turn connected by cable 19' to motor terminal 19". The ground or negative side of the circuit is connected to the frame which connects through plate 3 directly to the motor case.

Like numbers designate like parts in Figs. 10 1, 2 and 3.

I claim:

In combination with a frame comprising a square top member having a centrally located hole and downwardly extending members having 15 a platform with a centrally located hole, said platform located intermediate top member and lower ends of downwardly extending members, an electric motor pivotally mounted on said platform, the upper end of the motor case connected 20 to the lower end of an upwardly extending tube by means of studs and a plate, a T-member secured to the extreme upper end of said tube above the top face of said top member of the frame, tubular extensions extending horizontally in opposite directions from the T-member, a plurality of journals attached to the tubular extension members by bolts, a shaft in said journals arranged parallel to and above said extension members, said shaft having a mitre gear or a bevel pinion adjacent to T-member, means for mounting grinding wheels at ends of said shaft, and upwardly extending shaft inside the tubular member connected to end of motor's armature shaft by means of a coupling and having at its 25 upper end a gear engaging gear on the horizontal grinding wheel shaft, an insulated brush collar secured to tubular member above the end plate at lower end of the vertical shaft's plate member, a brush engaging said brush collar, a cable from the brush to motor's terminal, and a cable from brush to source of electric current, a ground-side cable from motor's pivot platform, a clamp surrounding the T-member and means for locking said clamp.

HANS SKREBERG.
